CHEWED GUM RECEPTACLE

Reva Harris Keston, Minneapolis, Minn.

Application May 22, 1946, Serial No. 671,536

1 Claim. (Cl. 206—37)

1

My present invention relates to improvements in receptacles and more particularly to a receptacle for holding a piece of chewed gum.

It has always been a problem for those addicted to the habit of chewing gum, when tired of chewing, where to store the same until again wanted or as to how to finally dispose of it.

The general practice in disposing of a piece of chewed gum is to stick the same on the underside of a piece of furniture or in public places it is often simply dropped on the floor and it is a well known fact that gum is very difficult to remove from the floor especially after it has been stepped on.

The object of this invention is to provide an attractive and extremely simple and highly efficient receptacle for holding a piece of chewed gum.

To the above end, generally stated, the invention consists of the novel construction, arrangement and combination of parts hereinafter described and defined in the claim.

In the accompanying drawing, which illustrates the invention, like characters indicate like parts throughout the several views.

Referring to the drawing:

Fig. 1 is a plan view of a blank, which when folded affords a chewed gum receptacle, and having attached thereto a barb for impaling a piece of chewed gum thereon;

Fig. 2 is an edge elevation of the blank shown in Fig. 1, with the barb bent into an upright position;

Fig. 3 is an end elevation of the receptacle;

Fig. 4 is a side elevation of the same;

Fig. 5 is a fragmentary view of a blank from which the barb is cut and pressed therefrom;

Fig. 6 is a sectional view taken on the irregular line 6—6 of Fig. 5, with the barb bent into an upright position;

Fig. 7 is an isometric view showing another form of the invention with the cover partly open, and

Fig. 8 is a view principally in longitudinal section taken centrally through the receptacle shown in Fig. 7, with the cover closed.

Referring first in detail to the invention shown in Figs. 1 to 4 inclusive, wherein the numeral 9 indicates a blank formed of a single piece of card-board or other suitable bendable material. This blank 9 has transverse folding lines or scores 10—10 and 11. On one end of the blank 9 is a tab 12 having therein a round hole 13. A transverse slot 14 is formed in the blank 9, outwardly

2

of the folding line 11, for the tab 12, as will presently appear.

The section of the blank 9, between the folding lines 10—10 afford the bottom member 15 of the receptacle and the two sections of the blank 9 outwardly of the bottom member 15 affords the two side members 16 of said receptacle. The section of the blank 9 outwardly of the folding line 11 afford a flap member 17.

10 A thin plate 18 of metal or other suitable material has an integral barb 19 for impaling a piece of chewed gum. This plate 18 is secured to the bottom member 15, by a wire staple 20, in a position in which when the barb 19 is bent into an upright position the same will be at the center of said bottom member.

When a person wishes to store a piece of chewed gum for future use, or to finally dispose of the same, the barb 19 is simply bent into an upright position and the gum impaled thereon. Next, the blank 9 is bent on the folding lines 10—10 to bring the side members 16 into upright positions. The tab 12 is next inserted through the slot 14 and the blank 9 bent on the folding line 11 to bring the flap 17 into overlapping arrangement with one of the side members 16, as shown in Figs. 3 and 4.

Referring now to the modification shown in Figs. 5 and 6 wherein parts that correspond to like parts shown in Figs. 1 to 4 inclusive are given the same reference numerals followed by a prime.

In this structure the barb 21 is cut from the bottom member 15' and when turned into an upright position as shown in Fig. 6, is bent on the line 22.

35 If the gum is to be saved for future use the receptacle may be placed in a purse or a pocket or the receptacle may be attached to a piece of clothing by means of a piece of string passed through the hole 13 and secured to the tab 12. 40 In discarding a piece of chewed gum the receptacle may simply be left on a table or otherwise finally disposed of.

Referring now in detail to the invention shown in Figs. 7 and 8, the numeral 23 indicates a cover equipped receptacle made of plastic or other suitable material. The receptacle 23 includes a body having a bottom member 24 and two side members 25. The edge of each side member 25 is a semicircle.

45 The receptacle 23 further includes a cover 26 hinged at 27 to the bottom member 24, between the side members 25. This cover 26, longitudinally, is semicircular and when closed rests on the edges of the side members 25 and forms a

complete closure for the body of the receptacle 23.

The cover 26 is releasably held closed by a spring catch 28 on the bottom member 24 and a small lug 29 on the inside of the cover 24. An upstanding barb 30, on which a piece of chewed gum may be impaled, is rigidly secured to the bottom member 24 at the center thereof.

In the structure shown in Figs. 1 to 6 inclusive, a piece of chewed gum may be impaled on either 10 of the barbs 19 or 21 without coming in contact with any part of the receptacle. Even after the receptacle 9 has once been folded, the ends thereof are open and afford ample room for a person's fingers when placing a piece of chewed gum on 15 the barb 19 or removing the same therefrom. This is also true of the structure shown in Figs. 7 and 8 wherein the ends of the receptacle 23 are open.

The receptacle 23 may be carried in a purse 20 or pocket or it may be provided with a safety pin for attaching the same to a piece of clothing.

From what has been said, it will be understood that the invention described is capable of modifications as to details of construction and arrangement within the scope of the invention herein disclosed and claimed.

What I claim is:

A receptacle of the class described formed of a single rectangular piece of material, having 30 three parallel transverse folding lines on which,

when the material is folded, forms of the material the bottom member and the two side members of the receptacle and a flap which forms an extension of one of the side members, a tab which forms an extension of the other side member, a slot in the folding line between the flap and the respective side member through which the tab may be inserted and bent into an upright position and the flap folded downwardly onto the other side member which, together with the tab, holds the side members in converging relation, the ends of the receptacle being open the entire distance between the bottom member and the top of the receptacle, and a foldable barb on the bottom member.
